UNITED STATES PATENT OFFICE.

CYRUS FISHER, OF CANTON, MASSACHUSETTS, ASSIGNOR TO HIMSELF AND
TOBIAS KOHN, OF HARTFORD, CONNECTICUT.

DESIGN FOR HOES.

Specification forming part of Design No. 5,201, dated August 15, 1871.

To all whom it may concern:

Be it known that I, CYRUS FISHER, of Canton, Massachusetts, have invented a new and Improved Design for Garden-Hoes, of which the following is a specification:

The accompanying drawing illustrates my invention.

The blade of the hoe is concave, with one round-pointed diamond end and one square end. The

sides are also of the peculiar form shown in the drawing.

I claim as my invention—

The design for a hoe, as shown.

CYRUS FISHER.
